UNITED STATES PATENT OFFICE.

FEALDON E. WATTON, OF ALTAMONT, ILLINOIS, ASSIGNOR OF ONE-HALF TO
GEORGE C. GOETTING, OF SAME PLACE.

WINDOW-SASH.

SPECIFICATION forming part of Letters Patent No. 438,042, dated October 7, 1890.

Application filed June 13, 1890. Serial No. 355,304. (No model.)

To all whom it may concern:

Be it known that I, FEALDON E. WATTON, of Altamont, in the county of Effingham and State of Illinois, have invented a certain 5 new and useful Improvement in Window-Sashes, &c., of which the following is a full, clear, and exact description, reference being had to the accompanying drawings, forming a part of this specification.

10 My invention relates to a window sash, shutter, blind, or screen so constructed that it may be adjusted to window-frames of different widths and fit tightly therein; and my invention consists in features of novelty, herein- 15 after fully described, and pointed out in the claims.

Figure I is an elevation of my improved sash in position in the frame of a window. Fig. II is a detail side elevation, part broken 20 away to show one of the plates. Fig. III is a similar view, in which but one plate is shown. Fig. IV is a cross-section taken on line IV IV, Fig. II. Fig. V is a cross-section taken on line V V, Fig. II. Fig. VI is a detail edge 25 view of the upper end of the adjustable strip, showing the ends of the plates bent over upon the top of the adjustable strip. Fig. VII shows my invention applied to a window-shutter, and Fig. VIII shows it applied to a 30 window-screen.

Referring to the drawings, 1 represents a window-sill, 2 the sides of the frame, and 3 a window having the usual upper and lower bars 4 and 5 and side bars 6 and 7.

35 Secured in the outer edge of the bar 7 are vertical plates 8, that extend beyond the edge of the bar 7 and are provided with slots 9.

10 is a bar or strip equal in length to the bar 7 and parallel therewith. The bar has 40 kerfs 12, in which the outer edges of the plates 8 work, and thus the bar 10 is kept in the same plane as the sash, the bar 10 being secured to the plates by pins 11, passing through the bar 10 and slots 9.

45 The ends 13 and 14 of the plates 8 are preferably bent over upon the upper and lower ends of the bars 7 and 10, as shown in Fig. VI.

Coil-springs 15 are seated in recesses 16 in the upper and lower parts of the bar 7, and 50 said springs bear against the strip 10 and

press it outward. In order to increase or diminish the power of the springs 15, their inner ends rest against the inturned end 15^a of the plate 15^b, the body of the plate occupying a recess in the sash and admitting of 55 endwise movement on a set-screw 15^c, which passes through a longitudinal slot 15^d in the plate.

Secured in the bar 10 near its upper and lower ends are dowel-pins or screws 17, whose 60 outer ends work in holes in the strip 7. The dowel-pins or screws may, however, be made fast in either bar.

In Fig. VII I have shown my invention applied to sliding shutters, such as are used in 65 the windows of railway-cars and buildings.

In Fig. VIII I have shown my invention as applied to window-screens.

I have described my invention as having two plates 8 for connecting the bar 7 and 70 strip 10; but in light windows, shutters, and screens there may be but one used, as I have shown in Fig. III.

The dowel-pins or screws 17 may be dispensed with in light work.

The side bars 6 and 10 of the screw may have grooves 18, as usual, to work on guide-ribs at the sides of the window-frame.

It will be seen that the sash, shutter, or screen will fit close in the frame, so that no 80 air or moisture can pass between the sash, &c., and the frame, nor between the bars 7 and 10.

The device has also another valuable feature, in that it forms a support for the sash, shutter, inside blind, or screen by the bearing of the bar 10 against the window-frame. For this reason balance-weights, with their 85 cords and sheaves, may be dispensed with.

Still another advantage is found in the device—namely, that the sash admits of such construction that it may be removed from the frame at any time by forcing the bar 7 in contact with the bar 10.

The operation of my device is as follows: 95 The parts being first connected, as described, the bar 10 is set into the usual groove in the window-frames and the sash grasped by the bar 6 and pressed toward the bar 10, causing the coil-springs 15 to contract and allow the 100

bar 7 to be pressed in contact with the bar 10. When the parts are thus contracted, the bar 6 may be placed in position in its groove in the frame, or the screw adjusted so the guide-strips rest in the grooves 18 and the bar 10 allowed to move outward, and thus the bars 6 and 10 are held tight against the window-frame.

By constructing a window sash, blind, or screen according to my invention it may be placed at any desired elevation, and will remain in that position without the use of weights or cords. It may also be easily moved into any other position.

15 The device also provides a tight connection between the sash and window-frame, whereby dust, &c., is prevented from entering, and should the sash or frame become shrunk or swelled from heat or rain the sash adjusts 20 itself to the changed conditions.

I claim as my invention—

1. The combination, in a window sash, blind, or screen, of the bar 7, plates 8, and bar 10, suitably connected to the plates with springs 25 forcing the bar 10 outward, substantially as and for the purpose set forth.

2. The combination, in a window sash, blind, or screen, of the bar 7, plates 8 secured therein, and a bar 10, adjustably connected to the plates by a pin passing therethrough and 30 working in slots in the plates, substantially as and for the purpose set forth.

3. The combination, in a window sash, blind, or screen, of the bar 7, plates 8, secured therein, bar 10, connected to the plates 8 by pins 11 35 working in slots 9 of the plates, and a spring 15, substantially as and for the purpose set forth.

4. The combination, with a window sash, blind, or screen, of a side bar 10, plate 8, forming a guide for the bar 10, and spring forcing the bar outward, substantially as set forth.

5. The combination, with a window sash, blind, or screen, of the plate 8, bar 10, spring 15, and the movable plate 15^b, forming a bearing for the inner end of the spring, substantially as set forth.

FEALDON E. WATTON.
